UNITED STATES PATENT OFFICE.

TYCHO VAN ALLER, OF SCHENECTADY, NEW YORK.

PENCIL-SHARPENER.

No. 892,335.

Specification of Letters Patent.

Patented June 30, 1908.

Application filed April 3, 1907. Serial No. 366,110.

To all whom it may concern:

Be it known that I, TYCHO VAN ALLER, a citizen of the United States, residing in Schenectady, county of Schenectady, State of New York, have invented certain new and useful Improvements in Pencil-Sharpener, of which the following is a specification.

The object of my invention is to provide a pencil sharpener that will facilitate the sharpening of pencils and produce superior results.

This sharpener is provided with two parallel guiding surfaces, one in the front and one in the rear of the cutting edge of the pencil-sharpening blade. The cutting edge of the blade is above the front guiding surface. This construction permits a uniform cut or shaving of the wood of the pencil regardless of the number of times the cutting edge of the blade has been sharpened, that is, within a reasonable limit, thus doing away with the adjusting of the blade, and the pressure exerted in sharpening the pencil does not come on the lead, but it is at all times on the wooden portion of the pencil. In beginning a cut, the wooden part of the pencil is drawn across the front guiding surface into engagement with the cutting edge of the blade which begins to shave the pencil, and then the wooden portion slides on the rear guiding surface until the completion of the cut, thus preventing any pressure on the lead which might tend to break it.

Pencil sharpeners made in accordance with my invention are simple in design and operation, and sharpen pencils in a perfect and very expeditious manner.

A further advantage of my invention lies in adapting the sharpener for finishing the point of the lead for special uses. The operation described produces a point well adapted for ordinary writing, but for drawing a chisel point or a very fine, round point is required. Heretofore in pencil sharpeners, it has been necessary to use an abrasive means for making such points, but with my improved device this additional feature is entirely eliminated by providing a small recess in the front guiding surface near the edge of the cutting blade to allow the pencil to be held at any desired angle while being drawn over the edge of the blade to shape the lead as desired.

Referring now to the accompanying drawing forming part of this specification, Figure 1 is a perspective view of a pencil sharpener

embodiment of my invention; Fig. 2 is an exploded perspective view showing parts of the pencil sharpener in detail, and Fig. 3 is a longitudinal section of the same, together with an illustration of a pencil in the process of being sharpened.

The pencil sharpener 1 is provided with a cover 2 that is hinged at 3 for the purpose of removing shavings in the interior of the receptacle 4 after pencils have been sharpened. Secured to the bottom of the pencil sharpener is a felt pad 5 that assists in preventing the sharpener from slipping when held by the hand on a flat surface, such as a desk, during the operation of sharpening a pencil. A cutting blade 7 is suitably supported on the cover 2.

In the form of the invention illustrated, blade-retaining guides 6 are secured to the cover for the purpose of receiving the pencil sharpening blade 7, which blade is held by a key 8 that slides under the blade and guides to secure the blade in place. If this key is drawn from under the blade 7 it may be removed. The blade 7 is cut away at 9 to engage the guides in order to prevent it from turning and to allow for the re-sharpening without changing the dimensions of the sides of the blade that are in contact with the guides 6. The inclined pencil guiding surfaces 10 and 11 are, respectively, on the cover 2 and the blade 7, the latter in rear of the cutting edge of the blade. These surfaces are parallel to each other and guide the wooden portion of the pencil so that no pressure is exerted on the lead to break it during the cutting operation.

In order to put a fine or chisel point on the pencil after it has been sharpened, recesses 12 are cut in the front guiding surface 10 near the outer edge and in front of the blade. This does away with the addition of any abrasive means, such as sand paper, and allows the lead of the pencil to be scraped when held at any angle to give any desired shape to the point.

To sharpen a pencil proceed as follows:— Hold the device against a flat surface, such as a desk, and place the end of pencil on the front guiding surface 10 and draw it towards the pencil sharpening blade 7; the first part of the wooden portion of the pencil coming in contact with the blade will be shaved off and the pencil will immediately thereafter slide on the rear parallel guiding surface 11, that is in rear of the cutting edge. This,

it will be noted, does not allow any pressure to be exerted on the lead, otherwise it would break and cause waste and extra labor. Should the user care to change or resharpen a blade, it will only be necessary to slide the key 8 from under the blade, allowing it to drop from the guides.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other equivalent means.

What I claim as new, and desire to secure by Letters Patent of the United States, is,—

1. In a pencil sharpener the combination of a support, a cutting blade having a plurality of cutting edges detachably mounted thereon and so arranged that it forms guiding surfaces at the rear of the cutting edges, and parallel guiding surfaces on the support in front of the cutting edges of said blade.

2. In a pencil sharpener, the combination of a receptacle, a cutting blade detachably mounted thereon, and parallel guiding surfaces in front and in rear of the cutting edge of said blade, the front guiding surface having a recess to allow for finishing the lead point of a pencil when sharpened.

3. In a pencil sharpener the combination of a receptacle, a cover therefor, a guiding surface on the cover, a cutting blade that forms a guiding surface in the rear of the cutting edge, means on the cover for holding the cutting blade parallel with the guiding surface on the cover, and a device for securing the blade in place.

4. In a pencil sharpener, the combination of a receptacle, a cover thereon, a guiding surface on said cover, a cutting blade that is mounted on the cover so arranged that it forms a guiding surface in rear of the cutting edge of the blade, and means integral with the said cover for receiving the cutting blade.

5. In a pencil sharpener, the combination of a receptacle, a hinged cover thereon, a guiding surface on said cover, in front of the cutting edge of the blade, a cutting blade that is detachably mounted on the cover having a guiding surface in rear of the cutting edge, means integral with the said cover for receiving the sides of the cutting blade, and a key for holding the cutting blade in a working position.

In witness whereof, I have hereunto set my hand this 1st day of April, 1907.

TYCHO VAN ALLER.
